UNITED STATES PATENT OFFICE.

GEORGE C. ROBERTS AND HENRY S. WILCOX, OF CHICAGO, ILLINOIS,
ASSIGNORS TO TROY LAUNDRY MACHINERY COMPANY, LIMITED, OF
TROY, NEW YORK, A CORPORATION OF NEW YORK.

STARCHING-MACHINE.

SPECIFICATION forming part of Letters Patent No. 739,722, dated September 22, 1903.

Application filed July 21, 1902. Serial No. 116,470. (No model.)

To all whom it may concern:

Be it known that we, GEORGE C. ROBERTS and HENRY S. WILCOX, citizens of the United States, residing at Chicago, in the county of Cook, State of Illinois, have invented certain new and useful Improvements in Starching-Machines, of which the following is a specification, reference being had therein to the accompanying drawings.

10 This invention relates to starching-machines, and has for its object to provide a construction in which all of the movable parts are adapted to be simultaneously raised from the starch-chest and also to improve the driving mechanism and other details of construction embodied in the machine, as hereinafter set forth, and defined by the appended claims.

In the drawings, Figure 1 is a side elevation of the machine; Fig. 2, a vertical section 20 thereof on the line 2 2 of Fig. 1; Fig. 3, a detail elevation of the foot carried by the swinging frame; Fig. 4, a perspective of the hood for the driving-gear; Fig. 5, a plan of the driving-worm and clutch; Fig. 6, an end 25 elevation thereof; Fig. 7, a detail elevation of the locking device between the swinging frame and base; Fig. 8, an end view of the same part; Fig. 9, a horizontal section through the bearing for one of the tension-rollers, and 30 Fig. 10 an elevation of a modification of the securing means between the swinging frame and base.

Like letters of reference refer to like parts in the several figures of the drawings.

35 The base or standards A, upon which the machine is supported, may be of any desired shape and are located at opposite sides of a starch-chest B, which is provided at its lower portion with a drain or draw-off cock B', 40 while the standards forming the base are connected together at suitable points by means of tie-rods A'. At the upper portion of these standards a receiving-table A² is located at one end and a delivery-table A³ at the opposite end, while between these tables a swinging frame C is suitably mounted upon a pivot C' to rest upon a base A⁴. The starch within the chest B is adapted to be heated by means of a steam-inlet pipe B², disposed at the

upper end of a condensing-chamber B³, the 50 lower end of which is provided with an exhaust-pipe B⁴. Leading from the upper portion of the chamber B³ is a steam-pipe B⁵, provided with a regulating-valve B⁶, from which a perforated injecting-pipe B⁷ extends laterally across the lower portion of the starch-chest for the purpose of agitating and heating the starch therein.

The starch-chest is entirely free of any of the operating mechanism, all of which is 50 mounted upon the swinging frame C, as shown by dotted lines in Fig. 1, wherein the main starching-roll C² is suitably journaled in a depending portion of the frame and has disposed concentrically thereto a series of auxiliary rolls C³, positively driven by a suitable pinion C¹¹, Fig. 2, upon one end of the roll C², engaging similar gears on rolls C³, which may be of any desired construction, preferably fluted or corrugated, as usual in this art. 7c The starching-roll C² is driven by a series of gear-teeth C⁴ thereon, which mesh with similar teeth carried by the fixed wringer-roll C⁶, while this roll is driven by a worm-gear C⁷, as shown in Fig. 2. This gear when the frame 75 is in its lowered position meshes with the threads of a worm D, mounted upon a driving-shaft D², which is provided with a driving-pulley D³, loosely mounted thereon, and the shaft is supported within suitable bearings D⁴, carried by brackets D⁵, extended from the standard A at one side of the machine. Upon this shaft a sliding clutch D⁶ is suitably keyed and provided with teeth D⁷, 85 carried by the driving-pulley, as shown in Fig. 5, while the sliding clutch is adapted to be pivotally supported from a bracket D⁹ by means of the yoke D¹⁰ and shifted on the shaft through the handle D¹¹. This worm is suitably incased upon its under face and sides by means of a shell D' to protect the same from contact with the goods operated upon or from injury in operating the machine. The worm-gear C⁷ is likewise protected by 95 means of a hood C⁸, extending over the outer face of the same and adapted to meet the casing D', so as to inclose these parts. This

hood is shown in detail at Fig. 4 and is supported by means of an arm C⁹, by which it is attached to the swinging frame C, and is provided with an extension C¹⁰, adapted to cover the upper portion of the worm D.

Above the fixed wringer-roll C⁶ an adjustable wringer-roll E is mounted, preferably, by means of a bearing E' at each side of the frame, slidably mounted within a way E², formed in the swinging frame, which bearing is adapted to be adjusted by means of a screw E³, mounted in the frame and acting against the pressure of a restoring-spring E⁴ beneath the bearing, so that the upper wringer-roll 15 may be adjusted to secure the desired pressure for extracting the proper amount of moisture from the starched goods. The goods are fed through this machine by means of tapes or bands, as shown in Fig. 2, one series F of which extends from a tension-roll F' downward over the upper wringer-roll and under the main starching-roll, thence between the wringer-rolls back to the tension-roll F', as shown by dotted lines in Fig. 1, 20 while the other series F² extends from a bearing-roll F³ at the feed end of the machine downward between the auxiliary starching-rolls C³ and the main starching-roll, thence upward between the wringers and over the 25 tension-roller F⁴, and thence downward beneath the starching-rollers C³ back to the bearing-roller F³. It will thus be seen that these tapes receive and convey the goods between them when passing between the starching-rollers and wringing-rollers and afterward separated toward the two tension-rollers, thus permitting a delivery of the goods upon the table A³. The belts are shown by dotted lines in Fig. 1 and full lines in Fig. 2, 30 but are those usually employed in this character of machine and therefore not specifically illustrated and described. For the purpose of adjusting the tension-rollers F' and F⁴ the frame C is provided with two horizontally-disposed ways F⁵, adapted to receive a rectangular bearing-block F⁶, formed to fit closely and slide within the ways and having a lug F⁷, suitably threaded to travel upon the adjusting-screw F⁸, which is provided with a 35 handle F⁹ to facilitate its operation, as shown in detail in Fig. 9, and each of the ways is similar in construction.

The swinging frame C is provided beyond its pivot with a foot G, adapted to rest upon a portion of the delivery-table A³ when the frame is in its raised position, as shown in detail in Fig. 3 and by dotted lines in Fig. 1. The opposite end of the frame is provided with a handle G' for raising and lowering the 55 same, and any desired means may be used for connecting the swinging frame to the base upon the standards—for instance, a link G², as shown in Figs. 7 and 8. This link may be pivotally mounted within a lateral lug G⁵ from the frame by means of a pin G⁴ and is adapted to lie within a slot formed in a similar lug G⁶, extending from the upper portion

of the standards A, while a locking-handle G⁶ is pivoted by a pin G⁷ to the lower end of the link and adapted to engage the under face of the lug G⁵, while all of the parts are inclosed and protected by means of a hood G⁸, secured to the lug G⁵ and extending downward, thus securing the swinging frame in its lowered position when the starching-rolls are submerged within the chest. In Fig. 10 a modified form of securing means between the swinging frame C and the base is shown, which consists of a hook pivoted at H' upon the swinging frame and adapted to engage a pin 8c or projection H² upon the base or standard.

In the operation of the machine the goods to be starched are introduced between the two tapes at one side of the starching-rolls and are carried between these rolls, so that the 85 corrugations thereof thoroughly work the starch into the fabric, which is thence carried by the tapes upward between the wringer-rolls, which extract the excess moisture, and then delivered by the separation of the tapes 90 in passing over their respective tension-rollers. It will be noted that all of the movable parts of this machine are mounted in the swinging frame, and therefore adapted to be instantly lifted from the starch-chest when 95 desired, while the construction of driving-gear permits this lifting without the necessity of shifting or disengaging any driving-belts and further provides a constant and steady driving motion best adapted to secure 100 the most efficient results in this art.

It will be obvious that changes may be made in the details of construction and configuration without departing from the spirit of the invention as defined by the appended 105 claims.

Having described our invention and set forth its merits, what we claim, and desire to secure by Letters Patent, is—

1. In a starching-machine, the combination 110 with the framework and the tank thereof, of a swinging frame having central fixed and concentric sides and bottom bearings, a main and auxiliary corrugated intermeshing starching-rolls mounted in said bearings, a worm-gear mounted on the shaft of said main starching-roll, means for locking said frame in its 115 lowest position, and a worm mounted on said framework to mesh with the gear on the shaft in the central fixed bearings of said swinging frame whereby said gear and worm are positively held in mesh when said frame is lowered.

2. In a starching-machine, standards, a starch-chest supported between the same, a 125 frame pivoted at one end above said starch-chest, starching and wringing rolls supported entirely within said frame, a feed-table at one side of said frame, a delivery-table at the opposite side thereof, a driving-shaft for said 130 rolls mounted upon one of said standards, a supporting-foot adapted to engage the table at the pivoted end of the frame, a securing device for the opposite end of said frame com-

prising a link pivoted to the frame and adapted to enter a slot in the base upon which the frame rests, and a handle pivoted to the lower end of the link to engage said base; substantially as specified.

3. In a starching-machine, a pivoted frame adapted to support a fixed wringer-roll, exterior means for driving said roll, an adjustable wringer-roll above the same, a main starching-roller driven from the fixed wringer-roll, auxiliary starching-rolls concentric to and positively driven by gearing thereon from the main starching-roll, adjustable tension-rollers at one side of said wringer-rollers, a tape or band passing over the upper wringer-roll, between the main and auxiliary starching-rollers and between the wringer-rollers to a tension-roller, a lower tape or band 30 passing between the starching-rollers and the wringing-rollers thence over a tension-roller separated from the first tension-roller, sliding bearings for said tension-rollers adapted to operate in parallel ways formed in the frame 40 and provided with a threaded lug projecting therefrom, and adjusting-screws mounted in the frame and passed through said lug; substantially as specified.

4. In a starching-machine, a pivoted frame adapted to support a fixed wringer-roll, means 25 for driving said roll, an adjustable wringer-roll above the same, a main starching-roller

driven positively by gearing thereon from the wringer-roll, auxiliary starching-rolls concentric to and positively driven by gearing thereon from the main starching-roll, adjustable 30 tension-rollers at one side of said wringer-rollers, a tape or band passing over the upper wringer-roll, between the main and auxiliary starching-rollers and between the wringer-rolls to a tension-roller, a lower tape or band 35 passing between the starching-rollers and the wringing-rollers thence over a tension-roller separated from the first tension-roller, sliding bearings for said tension-rollers adapted to operate in parallel ways formed in the frame 40 and provided with a threaded lug projecting therefrom, and adjusting-screws mounted in the frame and passed through said lug; substantially as specified.

In testimony whereof we affix our signatures in presence of two witnesses.

GEORGE C. ROBERTS.
HENRY S. WILCOX.
